CLAIM

The ornamental design for a suture package, as shown and described.

DESCRIPTION

FIG. 1 is a top perspective view of a suture package;

FIG. 2 is a top plan view;

FIG. 3 is a side view;

FIG. 4 is a side view;

FIG. 5 is a side view;

FIG. 6 is a side view;

FIG. 7 is a bottom plan view; and,

FIG. 8 is a bottom perspective view.

The broken lines immediately adjacent to the shaded areas represent the bounds of the claimed design while all other broken lines showing portions of the suture package are included for illustrating environmental structure and form no part of the claimed design.

1 Claim, 6 Drawing Sheets
